Term of patent 14 years

(Cl. D13—1)

FIG. 1

FIG. 2

FIG. 3

FIG. 1 is a perspective view of a telephone booth unit showing my new design;

FIG. 2 is a front elevational view thereof; and

FIG. 3 is a side elevational view thereof.

The telephones shown in broken lines are disclosed for illustrative purposes only.

The dominant features of my design reside in the portions shown in solid lines on the drawing.

I claim:

The ornamental design for a telephone booth unit, as shown and described.
